J. L. SCOTT.
NOTE SHEET FOR PLAYER PIANOS AND THE LIKE.
APPLICATION FILED OCT. 18, 1920.

1,413,293.

Patented Apr. 18, 1922.

UNITED STATES PATENT OFFICE.

JAMES L. SCOTT, OF MELBOURNE, VICTORIA, AUSTRALIA.

NOTE SHEET FOR PLAYER PIANOS AND THE LIKE.

1,413,293.

Specification of Letters Patent. Patented Apr. 18, 1922.

Application filed October 18, 1920. Serial No. 417,549.

To all whom it may concern:

Be it known that I, JAMES LIVESEY SCOTT, a subject of the King of Great Britain and Ireland, and a resident of the postal district 5 of Sunshine, in the shire of Braybrook, a suburb of the city of Melbourne, in the county of Bourke, State of Victoria, Commonwealth of Australia, (whose post-office address is Forrest Street, in the said postal 10 district of Sunshine,) have invented certain new and useful Improvements relating to Note Sheets for Player Pianos and the like, of which the following is a specification.

This invention relates to perforated note 15 sheets for mechanically operated pianos, organs and the like and its object is to provide means whereby an instrumental accompaniment may be played with such pianos and the like through the medium of written music 20 sic printed or otherwise inscribed on the face of the note sheet and arranged in such a manner that the accompanist may easily interpret the transcript as it is conveniently displayed before him by the unrolling of the 25 note sheet.

Referring to the drawings which form part of this specification:—

Figure 1 shows part of a note sheet in accordance with one embodiment of the invention.

Figure 2 shows portion of a note sheet in accordance with another embodiment, which is preferred to that seen in Figure 1.

Figure 3 shows portion of a note sheet in accordance with a further embodiment which is preferred to either of the forms seen in Figures 1 and 2.

Figure 4 is a diagrammatic perspective view showing a note sheet of the type seen in Figure 3 in use in combination with an inclined mirror which reflects the written music in a horizontal position for reading.

Figure 5 is a vertical sectional view taken through the front portion of a player piano or the like and showing the approximate relative disposition of the note sheet seen in Figure 3, and the mirror or reflector used in conjunction therewith. A bracket for supporting the mirror on the front of the piano is also shown.

Figure 6 is a front view of the bracket and mirror seen in Figure 5.

Figure 7 is a front view on a reduced scale of a player piano showing the invention in use in its preferred form.

In accordance with the embodiment seen

in Figure 1 the note sheet 2 has printed or inscribed on its front face to the right of the note perforations 3 and in a horizontal position a series of bars or passages of music indicated at 4 and providing the written bars or passages of the accompaniment to be played. These bars or passages are so arranged in relation to the note perforations that they are displayed to the accompanist 60 by the unrolling of the sheet at the proper time to enable him to render the accompaniment in harmony or accord with the piece played by the piano or the like. In other words each of the printed bars or passages 65 4 is arranged opposite or in horizontal alignment with the corresponding bar or passage represented by the note perforations. With this embodiment of the invention the accompanist is located to the right of the operator 70 of the piano or the like or in other convenient position to read the printed accompaniment as the horizontal bars or passages are displayed before him by the unwinding of 75 the note sheet. It will be evident that each 80 written bar or passage is displayed to the accompanist prior to the corresponding note perforations reaching the tracker bar 5 of the piano or the like. Thus the accompanist has ample time to memorize or become familiar with each section of the written accompaniment before it is necessary to play 85 same as the printed bars or passages reach the tracker bar simultaneously with the commencement of the corresponding perforated 90 note bars or passages.

In the embodiment seen in Figure 2 the written accompaniment is arranged on a continuous staff 6 extending longitudinally of the note sheet at the right hand side 95 thereof, the notes and other musical signs being arranged as shown for reading preferably from the right hand edge of the note sheet. It will be also seen that the written notes are arranged opposite or in 100 horizontal alignment with the leading end of the corresponding note perforations, the spaces between consecutive notes on the staff 6 being extended in accordance with the length of the corresponding note perforations so that the corresponding notes of the mechanically operated instrument and the accompanying instrument may be rendered together or in synchronism as the printed notes and the leading ends of the corresponding 105 or accompanying note perforations reach the tracker bar. The written notes of

the accompaniment are thus successively displayed on a continuous staff running parallel to the length of the sheet, the accompanist standing to the right of the note sheet or in other suitable position so that the printed notes may be conveniently read as the note sheet unwinds.

In the preferred embodiment of the invention as illustrated in Figures 3 to 7, the 10 written accompaniment is printed or inscribed on a continuous staff 7 extending longitudinally of the note sheet and at the right thereof. It will be observed however that the notes and other musical signs are 15 arranged in a reverse or back to front position and are also inverted as regards the arrangement of the written notes seen in Figure 2. That is to say the top line of the staff is disposed to the right and the 20 bottom line of the staff to the left instead of the opposite arrangement seen in Figure 2.

In combination with the note sheet seen in Figure 3 I employ a reflecting medium 25 in the form of a mirror 8 which is arranged in an inclined position as seen in Figures 4, 6, and 7, preferably at an angle of approximately forty-five degrees. This inclined mirror is disposed as near as possible to the side of the note sheet bearing the written music so that, as the note sheet unwinds, the printed accompaniment is reflected in the mirror and presented to the accompanist in a continuous horizontal line 30 35 moving from right to left as indicated by the horizontal arrow in Figure 4, the other arrow in this figure indicating the direction of movement of the note sheet.

With this preferred embodiment of the 40 invention, the accompanist is located in convenient position to observe in the mirror the reflection of the music as it appears to move horizontally with the notes in upright or normal position to be played at the proper 45 time in synchronism with the corresponding or accompanying notes of the piano or the like.

The mirror 8 may be mounted as seen in Figures 5 and 6 upon a bracket 9 attached 50 to the front 11 of the piano or the like. This bracket preferably comprises an inner or rear member 12 and an outer or front member 13 connected by a bridge or top member 14 which passes over the lower edge 55 15 of the usual note sheet opening in the front of the piano or the like.

The bracket is held in position by a clamping plate 16 which is disposed between the front member 13 and the front face of the 60 piano and is provided with a felt or like pad 17 adapted to be pressed against the front of the piano by a clamping screw 18 which passes through the front member 13 and is connected at its inner end to the 65 clamping plate 16 in such a manner that

the felt pad may be pressed against the front of the piano without rotation of the clamping plate with its screw.

The bracket 9 also carries a socket 21 through which is a vertical hole to accommodate a supporting stem 22 which may be attached either fixedly or adjustably to a mirror frame 23 carrying the inclined mirror 8. In Figure 7 the mirror is shown fixed to the supporting stem 22 at the proper 75 inclined attitude, whilst in Figure 6 the mirror is angularly adjustable and may be locked in any desired position by means of a locking screw 25 carried on the upper end of the supporting stem. The mirror 80 may also be vertically adjusted with the stem 22 by means of an adjusting screw 26 passing through the wall of the socket 21 and engaging the side of the stem 22.

Instead of the mirror arrangement above 85 described I may employ a suitable arrangement of prisms or lenses, or both adapted to project the image of the written accompaniment onto a ground mirror or reflector conveniently arranged for observation by 90 the accompanist.

The invention provides a simple, effective and inexpensive means whereby a player piano or the like may be accompanied for instance, by a violin or a reed or brass 95 instrument without any other written music than that carried by the note sheet itself.

It will be obvious that although in this specification the written music on the note sheet has been referred to as the accompaniment, it may in a strict musical sense provide the theme or melody of the piece being played, whilst the accompaniment as usually understood in musical terms is provided by the note perforations. As in actual fact however either instrument undoubtedly accompanies the other, the term 100 accompaniment as herein applied to the written music will be clearly understood and interpreted accordingly.

Having now described my invention what I claim as new and desire to secure by Letters Patent is:—

1. The combination of a note sheet having inscribed on its front surface a written instrumental accompaniment to the music rendered by the note perforations, said written accompaniment being arranged on a continuous staff extending longitudinally of the note sheet and having its written 115 musical notes and signs reversed, and a reflector positioned to reflect said written accompaniment in a substantially horizontal line and in normal position to the accompanist as the note sheet unwinds.

2. The combination of a note sheet having inscribed on its front surface a written instrumental accompaniment to the music rendered by the note perforations, said written accompaniment being arranged on 120

a continuous staff extending longitudinally of the note sheet to one side thereof and having its written musical notes and signs reversed, and an inclined mirror positioned adjacent the side of the note sheet bearing the written accompaniment, for the purpose set forth.

3. The combination of a note sheet having inscribed on its front surface a written instrumental accompaniment to the music rendered by the note perforations, said written accompaniment being arranged on a continuous staff extending longitudinally of the note sheet to one side thereof and having its written musical notes and signs reversed, an inclined mirror mounted on the front of the piano and means for adjusting the position of said mirror, for the purpose set forth.
- 10 4. The combination of a note sheet having inscribed on its front surface a written instrumental accompaniment to the music rendered by the note perforations, said written accompaniment being arranged on a continuous staff extending longitudinally of the note sheet and having its written musical notes and signs reversed, a bracket attached to the front of the piano, a mirror mounted on said bracket, means for adjusting the position of the bracket in relation to the note sheet, and means for adjusting the position of the mirror in relation to the bracket, for the purpose set forth.
- 15 5. The combination of a note sheet having inscribed on its front surface a written instrumental accompaniment to the music rendered by the note perforations, said written accompaniment being arranged on a continuous staff extending longitudinally of the note sheet near one side thereof and having its written musical notes and signs reversed, an inclined mirror positioned ad-

jacent the side of the note sheet bearing the written accompaniment, a bracket mounted on the front of the piano to support the mirror, means for clamping said bracket in desired horizontal position, a socket carried by the bracket, a vertical stem passing through said socket and carrying the mirror, and means for adjusting said stem vertically within the socket.

6. The combination of a note sheet having inscribed on its front surface a written instrumental accompaniment to the music rendered by the note perforations, said written accompaniment being arranged on a continuous staff extending longitudinally of the note sheet near one side thereof and having its written musical notes and signs reversed, an inclined mirror positioned adjacent the side of the note sheet bearing the written accompaniment, a bracket mounted on the front of the piano to support the mirror, means for clamping said bracket in desired horizontal position, a socket carried by the bracket, a stem passing through said socket and carrying the mirror, means for adjusting said stem vertically within the socket, and means for angularly adjusting the mirror on said stem substantially as described.

7. A note sheet having inscribed on its front surface a written instrumental accompaniment to the music rendered by the note perforations, said written accompaniment being arranged on a continuous staff, extending longitudinally of the note sheet to one side thereof and having its written musical notes and signs reversed.

In testimony whereof I affix my signature.

J. L. SCOTT.
